UNITED STATES PATENT OFFICE.

JULIUS C. LOWRY, OF DETROIT, MICHIGAN.

DESIGN FOR AN ELECTRIC-LIGHTING FIXTURE.

Application filed June 18, 1925. Serial No. 13,814. Term of patent 14 years.

To all whom it may concern:

Be it known that I, JULIUS C. LOWRY, a citizen of the United States, residing at Detroit, in the county of Wayne and State of Michigan, have invented a new, original, and ornamental Design for Electric-Lighting Fixtures, of which the following is a specification, reference being had to the accompanying drawing, forming part thereof.

Fig. 1 is an elevation of an electric lighting fixture embodying my invention.

Fig. 2 is a fragmentary view of the cap indicating in enlarged detail the ornamentation on the top surface thereof.

Fig. 3 is a similar view showing the ornamentation on the bottom surface thereof.

I claim:

The ornamental design for an electric lighting fixture as shown.

JULIUS C. LOWRY.
